NESTING PAPER CAN

William F. Goez, Keokuk, Iowa, assignor of one-half to Iowa Fiber Box Company, Keokuk, Iowa, a corporation of Delaware, and one-half to South West Box Company, Sand Springs, Okla., a corporation of Delaware

Application March 23, 1932, Serial No. 600,798

4 Claims. (Cl. 229—5.5)

This invention relates to containers and, among other objects, aims to provide an improved container which may be used satisfactorily to replace the metal cans in which ice-cream is packed for the retail trade, the particular object being to provide a paper can of ample strength which may be nested, for economy in shipping and in storage space, yet may be tightly closed at the top by a flanged cover or cap and will have an unusually strong and leak-proof bottom construction.

This application is a companion to application Serial No. 600,797 filed March 23, 1932.

In the drawings, showing a preferred embodiment of the invention,—

Fig. 1 is a side elevation of the improved can; Fig. 2 is an enlarged fragmentary sectional view taken on the line 2—2 of Fig. 1, and showing the cover for the can;

Fig. 3 is an enlarged fragmentary sectional view taken on line 3—3 of Fig. 1;

Fig. 4 is a top plan view of the can;

Fig. 5 is a horizontal sectional view taken on line 5—5 of Fig. 3 but drawn on the scale of Fig. 1;

Fig. 6 is a fragmentary view of the lower portion of the blank from which the container is made;

Fig. 7 is a horizontal sectional view taken on the line 7—7 of Fig. 2, but drawn on the scale of Fig. 1; and

Fig. 8 is a fragmentary view of the blank from which the cover flange is made.

Paper containers are in use for holding small quantities of ice-cream and other foodstuffs but so far as I know, there are no satisfactory paper cans, capable of holding one to ten gallons of ice-cream or other semi-solids, which can withstand the usage which such containers receive in shipping, trucking and refrigerating. The present invention provides an improved paper can which meets all of the requirements of the ice-cream trade and which may also be nested so as to require a minimum of space during shipment or when stored empty.

Referring particularly to the drawings, there is shown a paper can 10 having a frusto-conical body portion 11 of slight taper, the large end being at the top of the container, so that the empty containers may be nested. The body is conveniently formed by wrapping a sheet of heavy, treated paper board around a tapered mandrel and securing the overlapping edges together by suitable stitches 12. These stitches

may be applied by a traveling stitching head (not shown), while the blank is held on the mandrel.

In order that a cap or cover 13 may be frictionally secured on the container and at the same time to provide a flange by which the container may be gripped for lifting and carrying, the upper portion of the frusto-conical container is built out so as to be cylindrical. Herein, a collar 14 of heavy, stiff paper, having its lower portion bent inwardly and upwardly, as at 15, is secured to the upper portion of the body 11 on the outside by glue or the like. The upper edge of the collar 14 contacts with the body 11 while the lower portion is spaced a sufficient amount from the body by the inwardly and upwardly bent portion 15, so that the outer surface of the collar 14 is substantially cylindrical. An outer collar member 16, also of heavy paper, is secured as by glue outside of the collar 14, and its lower edge provides a flange under which a can lifter 17 may be engaged, the width of the collar 16 being such that it conveniently accommodates can lifters at present in use, so that the can may be lifted out of a refrigerating compartment or truck body.

The width of the inner collar 14 exceeds that of the collar 16, so that its lower edge is below the natural nesting point of the can; thus, when the cans are nested, the flange 17 formed by the lower edge of the collar 14 engages the top of the next lower can 10a (indicated in dotted lines in Fig. 2) to prevent the cans from being wedged together, which would make the nested containers difficult to separate. The double thickness collar provides a strong reinforcement for the container at the top edge, as well as a friction surface for the cap 13, to be described.

The blank from which the container is made, a portion of which is shown in Fig. 6, is provided at its lower end with a series of integral tongues 18, shaped somewhat like gear teeth, the purpose of which is to interlock the side wall of the can with the bottom. The lower end of the blank is adapted to be bent on the dotted lines 19, 20 and 21 to form a kind of bead (Fig. 3) for strengthening the bottom of the can. The blank is bent inwardly on line 21 and then upwardly on line 20 to form an inner wall 22, which is spaced from the outer wall, as shown in Fig. 3, and the tongues 18 are then bent inwardly on line 19 forming a circular, inwardly extending flange. To further strengthen the bead at the lower end of the container, a relatively thick ring 23 of heavy paper board is secured between the inner and outer walls by glue.

The bottom of the container is made of at least two disks of fiber board 24 and 25, the disk 24 being above the flange formed by the tongues 18 and glued thereto. The other disk 25 is glued 5 at its marginal portion to the undersides of the tongues 18 and at its central portion to the underside of disk 24, as will be clear from Fig. 3. The diameter of the disk 24 is such that it can be inserted as far as its final position only by a 10 press fit, without buckling however, and thus very tightly engages the inner wall of the container. The edge of the disk 25 is likewise secured by a press fit against the inner wall 22. The tongues 18 present ample surface for the 15 glue to form a strong joint, and are so shaped that the tongues for another blank are provided by the material between them, thus effecting a saving of material when cutting out the blanks. Another advantage of the tongues is that there, 20 are no points to become bent in handling.

The cover 13 may be formed in a manner similar to the bottom of the container, except that no bead is necessary. The blank from which the flange of the cover is made (a portion of which 25 is shown in Fig. 8) comprises an elongated strip of material having integral tongues 26 similar to tongues 18. The flange blank is bent into cylindrical form, the ends being overlapped and secured together, forming a flange 27, the inner 30 diameter of which is substantially the same as the outside diameter of the collar 16, so as to be frictionally secured thereto. The tongues 26 are bent inwardly on line 28 to provide an inner circumferential flange. A disk 29, preferably of corrugated board, is glued to the underside of the flange so formed and a disk 30 of paper is glued to the outer side of the flange and to the disk 29. This construction provides a reinforced cap which is sufficiently strong to protect the top of the container and its contents 35 from damage. The container and its cover are treated on their interior surfaces, so as to be moisture-proof, preferably in accordance with the disclosure of application Ser. No. 586,630, filed January 14, 1932 and assigned to the assignee 40 of this application, thus making the containers particularly adapted for use with ice-cream, butter, lard or other similar materials.

The reinforcing collars at the top and bottom 45 of the container and the glued disks and ring of tongues at the bottom together with the bead result in a strong and durable container which will withstand much abuse. At the same time, the container is so inexpensive that it may be 50 discarded after being once used, and in this respect it effects considerable savings in handling,

express, trucking and other charges, as well as the elimination of the expensive washing and sterilizing which all metal cans are subjected to before reuse.

Obviously, the present invention is not restricted to the particular embodiment thereof herein shown and described. 5

What I claim is:

1. A nesting container comprising, in combination, a frusto-conical body made from a 10 single sheet of flexible paper board; and a reinforcing collar secured to the upper portion of the container, said collar having its lower end bent inwardly and extending upwardly to space the lower end of the collar from the frusto-conical 15 side wall; the outside wall of said collar being cylindrical.

2. A nesting container comprising, in combination, a frusto-conical body made from a single sheet of flexible paper board whose edges are 20 overlapped and secured together; a reinforcing collar secured to the upper portion of the container, said collar having its lower end bent inwardly and upwardly to space the lower end of the collar from the frusto-conical side wall; 25 the outside of said collar being cylindrical; and a second cylindrical collar secured to the first cylindrical collar on the outside and having its lower edge above the lower edge of the first collar.

3. A nesting container comprising a frusto-conical body of treated paper; a collar consisting of a paper ring secured on the outside of said body at the upper end, said paper ring having its lower edge doubled under, so as to cause the outer face of the ring to stand out from the 30 frusto-conical body, and thus provide a cylindrical outer face adapted to frictionally hold a flanged cover; the lower edge of said collar being below the natural nesting point of the container, to obviate the jamming of two nested 35 containers. 40

4. A nesting container comprising a frusto-conical body of treated paper; a collar consisting of a paper ring secured on the outside of said body at the upper end, said paper ring having its lower edge doubled under, so as to cause the outer face of the ring to stand out from the frusto-conical body, and thus provide a cylindrical outer face; the lower edge of said collar being below the natural nesting point of the container, to obviate the jamming of two nested 45 containers; and another cylindrical collar surrounding and secured to the first but of less width, and so positioned that its lower edge is spaced above the lower, doubled edge of the first collar. 50
